UNITED STATES PATENT OFFICE

NICOLAS MONNIER, OF VALENCE, FRANCE

NUT-LOCK DEVICE

Original application filed October 28, 1927, Serial No. 229,508, and in France May 25, 1927. Divided and this application filed November 17, 1928. Serial No. 320,158.

The present invention which is a division of my copending application No. 229,508 filed October 28, 1927, relates to a modified embodiment of a nut-lock of the type described and broadly claimed in the above mentioned patent application.

An object of the invention is to provide a nut-lock of the general type disclosed in the main patent application and which will 10 be chiefly suitable for heavy bolts such as the bolts for railway fish-plates.

Another object of the invention is to provide means whereby the locking spring may occupy various positions with respect to the 15 carrying member.

A further object resides in the provision of a nut-lock of the type referred to which will be efficient and durable in operation, although easy to be manufactured at a very 20 small cost.

With the above and other objects in view, the invention consists in the details of construction and in the arrangement and combination of parts to be hereinafter more fully 25 described and particularly pointed out in the appended claims.

The invention will be now specified with reference to the appended drawing, showing solely by way of example a preferred embodiment of the invention and in which

Fig. 1 is a plan view of a nut-lock provided with a hook-shaped spring.

Figs. 1^a and 1^b relate to the functioning of the embodiment shown in Fig. 1.

Fig. 2 shows a similar device provided with two springs.

And Fig. 3 shows a like device, in elevational and plan views in which the spring comprises a bent operating branch.

As represented in Fig. 1, the device comprises a carrying member A adapted to be screwed upon a threaded rod R, and a spring B, made of piano wire and having the form of a simple hooked piece with two unequal branches y—z, a small boss or shoulder z¹ being provided on the branch z. As described in the main patent, the carrying member A is constituted by a cap provided with a central aperture and a flange. The edge h of the 50 central aperture of the said member is given

the form of a helix having the same pitch as the nut with which the device is to be used; this form can be given to the edge h by the pressing process, after making a slight slot l whereby the said form may be produced, or 55 by like means. In all cases the edge h which is thus shaped is given the outline of a helix having the same pitch as the corresponding nut.

According to the present invention, the upper edge of the flange is turned in so as to form a kind of groove for the purpose of maintaining the spring in a plane perpendicular to the axis of the bolt. Further the lateral flange is provided with a plurality of 60 recesses x or openings, the cap being thus given a castellated shape.

The operation is as follows. With the braking device mounted in place, as shown in Fig. 1, the branches y and z will tend to move apart; the point p is jammed into the thread of the bolt; the boss z¹ of the branch z will bear upon the groove of the device and against the edge of one of the apertures x whilst the branch d bears against the edge 70 of another aperture x. To remove the braking device, I dispose (Fig. 1^a) the pierced end of the spindle H upon the end of the branch z and operate the device by three movements: (1) The branch z is bent in the 75 direction of the arrow 1 so as to disengage the boss z¹ from the edge of the aperture;

(2) due to its elasticity the branch z will move in the other direction according to the arrow 2 and is thus removed by its own action from the groove of the device; (3) I push upon the hook according to the arrow 3, and said hook will be at once released from the screw thread.

To place the device in position (Fig. 1^b) 90 I first screw the device A upon the bolt until it makes contact with the nut, and then operate by hand to dispose the hook as represented, with the large branch z extending from one of the said apertures, the small branch y being engaged in the thread of the bolt; I then use the spindle H to drive the branch z in the direction of the arrow 5 so as to bring the loop d into one of the apertures, and some force must be used, since the two 100

branches of the hook are to be brought together in this movement.

As shown in Fig. 2, the device may comprise two braking springs in the symmetrical position, and in this manner the device A cannot be screwed or unscrewed.

Fig. 3 shows a like construction having one or two braking springs, but herein the branches *z* are bent at right angles at V to allow hand operation of the device by means of its bent ends, without requiring the use of the spindle H.

Obviously the carrying member A may be constituted by the nut itself provided with a recess adjacent the threaded hole and the several parts composing the braking device may be varied in any suitable manner as to shape, size and disposition without departing from the scope of the invention as hereinafter claimed.

Having now described my invention what I claim as new and desire to secure by Letters Patent is:

1. A nut-lock comprising in combination a screwthreaded rod, a member adapted to be screwed thereupon, and provided with an annular recess adjacent said rod, a spring wire carried by said member, means for holding said spring in a plane perpendicular to the axis of said rod, said spring being provided with a U-shaped portion, a plurality of openings in the wall bounding said recess, each of which being adapted to receive and seat the rounded part of said U-shaped portion, one end thereof engaging the threads of the rod, and the other branch resiliently engaging the wall of said recess.

2. A nut-lock comprising in combination a screwthreaded rod, a member adapted to be screwed thereupon and provided with an annular recess adjacent said rod, a wire spring carried by said member, means for holding said spring in a plane perpendicular to the axis of the rod, said spring being provided with a U-shaped portion, a plurality of notches in the wall bounding said recess so as to form a castellated member, each of said notches being adapted to receive and seat the rounded part of said U-shaped portion, one end thereof engaging the threads of the rod and the other branch resiliently engaging the wall of said recess.

3. A nut-lock comprising in combination with a screwthreaded rod, a member adapted to be screwed upon said rod and provided with an annular recess adjacent said rod, a spring wire comprising a U-shaped portion, the rounded part of said U engaging an aperture provided in the wall bounding said recess, the shortest branch of said U-spring being adapted to jam against the said threaded rod, while an abutment is provided on the other branch for resiliently engaging the edge of another aperture cut out in said

wall bounding the recess whereby the spring is held in its operative position.

4. A nut-lock comprising in combination with a screwthreaded rod, a member adapted to be screwed thereupon and provided with an annular recess adjacent said rod, a groove in the internal wall bounding said recess, a plurality of spaced notches cut out in said wall, a spring wire comprising a U-shaped portion, the rounded part of said U engaging one of said notches, the shortest branch of said U-spring engaging the bolt threads and a projecting part being provided on the other branch for cooperating with one of the other notches and resiliently pressing the jamming branch against the bolt threads.

5. A nut-lock comprising in combination with a screwthreaded rod a nut, a cap having a central aperture in the bottom and a lateral flange the upper edge thereof being turned in so as to form a kind of groove, said flange being cut out so as to form a castellated cap, a slot in said bottom, the edge of said central aperture being stamped into a helical surface adapted to cooperate with the threads of the rod whereby said cap may be screwed thereon above the nut, a spring wire comprising a U-shaped portion, the rounded part of said U engaging any one of said channel-shaped notches, the shortest branch of said U spring engaging the bolt threads, the other branch being bent so as to form an abutment cooperating with the edge of another notch for holding the spring in jamming position.

6. A nut lock comprising in combination a screwthreaded rod, a member adapted to be screwed thereupon and provided with an annular recess adjacent said rod, a spring wire carried by said member, means for holding said spring in a plane substantially perpendicular to the axis of said rod, said spring having substantially the form of a U-shaped hook with two substantially straight branches of unequal length, at last two openings in the wall bounding said recess whereof one is adapted to receive and seat the rounded part of said U-shaped hook, the shorter branch of the hook engaging the threads of the rod and the other branch extending outwardly of the carrying member through the other opening.

7. A nut lock comprising in combination a screwthreaded rod, a member adapted to be screwed thereupon, a wire spring having substantially the form of a hook with two substantially straight branches of unequal length, the apex of said hook being pivotally mounted on said member in such a manner that the end of the shortest branch may engage the threads of the rod at a point situated forwardly in the unscrewing direction of the carrying member of the line joining the axis of the threaded rod to the axis of pivotatation and an abutment on said spring

carrying member, the outer side of the longer branch of the hook engaging said abutment, whereby the spring is held in a state of elastic deformation and the shortest branch is resiliently pressed against the threads.

5 In testimony whereof I have signed my name to this specification.

NICOLAS MONNIER.
